(57) CLAIM

The ornamental design for a combination lamp for an automobile, as shown and described.

DESCRIPTION

FIG. 1 is a right front perspective view of a combination lamp for an automobile showing my new design, wherein the rear and projection outside the peripheral rim on the lower left forms no part of the claimed design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof; and,

FIG. 7 is a rear elevational view thereof.

My design includes mirror images of the embodiments depicted herein.
